UNITED STATES PATENT OFFICE.

WALTER J. FROST, OF KENOSHA, WISCONSIN, ASSIGNOR TO THE BADGER BRASS MANUFACTURING COMPANY, OF SAME PLACE.

LAMP-BRACKET.

SPECIFICATION forming part of Letters Patent No. 663,121, dated December 4, 1900.

Application filed March 17, 1900. Serial No. 9,126. (No model.)

To all whom it may concern:

Be it known that I, WALTER J. FROST, of Kenosha, Wisconsin, have invented certain new and useful Improvements in Lamp-Brackets, of which the following is a specification.

This invention relates to improvements in adjustable brackets, and refers more specifically to an improved bracket particularly adapted for use in supporting vehicle-lamps and the like.

The object of the invention is to provide a simple and reliable construction all of the principal parts of which may be struck up from sheet metal by means of dies, thereby reducing the cost of manufacture to a minimum and insuring absolute interchangeability of parts and at the same time provide certain features of adjustment whereby the clamp may be set and held rigidly and positively at certain fixed angles only with relation to the clamp members of the bracket.

The invention consists in the matters hereinafter described, and more particularly pointed out in the appended claims and will be readily understood from the following description, reference being had to the accompanying drawings, in which—

Figure 1 is an elevation of a bracket embodying my invention, fragmentary parts of the lamp and the support to which the lamp is attached by means of the bracket being shown also. Fig. 2 is a top plan view of the bracket. Fig. 3 is a fragmentary detail view of one pair of the pivot-ears. Fig. 4 is a top plan view of the adjustable bracket-arm disconnected from the other parts. Fig. 5 is a detail view of the main pivot-bolt or pintle by means of which the clamping-jaws are united to the adjustable bracket-arm.

Referring to said drawings, 12 designate the two clamping-jaws, each consisting of a strap form of sheet metal provided at a point intermediate of its length with a main gripping portion 3, conformed to fit the support to which it is designed to be applied, in the present instance made semicircular to embrace a tubular or cylindric part and provided at one end with a pair of pivot-ears, as indicated at 4 and 5, respectively, formed integrally with the main body of the jaw and arranged to stand in planes parallel with each

other and with the plane of movement of the clamping-jaws, while at its opposite end each jaw is provided with an extension 6, apertured to receive a clamping-bolt 7 and terminating in a second gripping or clamping portion 8, conformed to engage a support of different cross-sectional form from that for which the main gripping portion is constructed—as, for example, the fork-arm of a velocipede. The extensions 6 are desirably and, as herein shown, each provided with a longitudinally-extending rib or relatively broad bead 9, struck up by means of the forming-die, to add rigidity to said extensions and at the same time afford suitable bearing surfaces or seats against which the head 10 and nut 11 of the clamping-bolt may respectively bear. The pair of pivot-ears of one of said clamping members—in this instance the pair designated by the numerals 5—are provided with rectangular or other non-circular pivot-apertures to receive and hold from rotation a correspondingly-shaped pintle or pivot-bolt 12, while the opposite pair of ears 4 are provided with circular pivot-apertures of sufficient diameter to permit the clamping-jaw to move upon the non-circular pintle, the object of this construction being to hold said pintle positively against rotation with relation to one of the clamping-jaws and through means holding the pintle rigid with the connected part of the bracket to thereby enable the lamp to be held rigidly at certain fixed angles with relation to the support.

14 designates as a whole an adjustable bracket-arm, by means of which the clamping-jaws are adjustably united with a rigid part of a lamp. In the improved construction shown herein said bracket-arm comprises a pair of duplicate plates 15, secured together in register with each other by means of a plurality of rivets 16, each member being provided at one end with a pivot-ear 17, desirably made circular in marginal conformation, centrally apertured, as indicated at 18, and provided upon its inner face around its aperture with a series of radial corrugations or ribs 19. At its opposite end each bracket-arm member is provided with a transversely-extending recess or groove 20, V-shaped in the present instance, the recesses of the two

members being constructed to form when the members are secured together in register a suitable socket to receive and hold from rotation the pintle 12.

5 21 designates as a whole an ordinary thumb nut and bolt adapted to extend through the clamping-ears and by means of which the latter may be clamped into fixed engagement with a rigid bracket-arm 22, secured upon the 10 lamp. The bracket-arm 22 is of common construction, consisting in the present instance of a pair of plates secured together, so as to form practically a single arm, which is provided at its end with an ear 23, desirably 15 conformed to the general outline of the ears of the adjustable bracket-arm and provided upon both of its surfaces with corrugations or depressions 24, adapted to register with the radial ribs of the clamping-ears. In order to 20 facilitate the engagement of the lamp with the adjustable bracket-arm or its detachment therefrom, the ear 23 is slotted from its bolt-aperture radially outward, preferably in a downward direction, as indicated by the dotted 25 lines at 25.

In adjusting the bracket it will be obvious that by reason of the polygonal form of the pintle and the correspondingly-shaped socket within which it fits the lamp will be positively 30 held in whichever one of the three positions of angularity it may be set—viz., with the bracket straight or with the bracket-arm extending at right angles to the clamping-jaws in either direction, whether the pintle-bolt remains absolutely tight or not. Obviously a 35 greater or less number of positions of adjustment could be provided by simply changing the cross-sectional form of the polygonal pintle and the socket within which it fits.

40 It will be seen from the foregoing description that all of the several parts of the bracket, with the exception of the several bolts, may be readily struck out by means of suitable dies, thus insuring economy of manufacture 45 and absolute interchangeability of parts and at the same time producing a structure which is strong and reliable in action and which may be adjusted to any one of the several positions with the utmost facility.

50 It will be further obvious that the several details of construction may be modified to a certain extent without departing from the invention, and I do not therefore wish to be limited to the exact details shown except as 55 made the subject of specific claims.

I claim as my invention—

1. An adjustable bracket for vehicle-lamps, comprising a pair of clamping-jaws, each jaw consisting of a sheet-metal strap-form member, provided at a point intermediate of its 60 length with a gripping portion adapted to engage a support, a pair of pivot-ears formed integrally with one of its ends and arranged in planes parallel with each other and with the plane of movement of the jaw and at 65 its opposite end with an integral extension terminating in a second differently-shaped gripping portion adapted to engage a support, a clamping-bolt arranged to extend through the extensions of the clamping-jaws at a point 70 between the two gripping portions thereof, an adjustable bracket-arm consisting of two stamped plate members rigidly united, with corresponding parts in register with each other, each provided at one end with a crease 75 to form a pivot-socket and at its opposite end with an apertured clamping-ear, a rigid bracket-arm adapted to be permanently secured to the lamp and provided at its projecting end with a slotted ear adapted to fit between the clamping-ears of the adjustable bracket, interfitting projections and recesses formed upon the meeting faces of the adjustable and rigid bracket-ears, a clamping-bolt extended through said ears and a combined 80 pintle and clamping-bolt extended through the ears of the clamping-jaws and the socket formed between the two members of the adjustable bracket-arm, said socket-recesses and an ear of one of the clamping-jaws being made 85 of non-circular form in cross-section and the combined pintle and clamping-bolt being made of corresponding non-circular form in cross-section, substantially as and for the 90 purposes described. 95

2. In a lamp-bracket, an adjustable bracket-arm consisting of two plate members rigidly united face to face, with corresponding parts in register with each other, each provided at one end with a transversely-extending crease 100 forming a pivot-socket recess of non-circular form in cross-section, and at its opposite end with an apertured clamping-ear and series of radial corrugations surrounding said apertures upon the proximate faces of said ears, 105 substantially as described.

WALTER J. FROST.
